BY David T. Simms, ATTORNEYS.

UNITED STATES PATENT OFFICE.

JOHN C. SCHELTER, OF PITTSFORD, NEW YORK.

LAST.

Application filed June 4, 1921. Serial No. 474,899.

To all whom it may concern:

Be it known that I, JOHN C. SCHELTER, a citizen of the United States, and resident of Pittsford, in the county of Monroe and State 5 of New York, have invented certain new and useful Improvements in Lasts, of which the following is a specification.

The present invention relates to lasts and more particularly to the type in which the 10 heel part and the toe part are movably connected together so that the last may be collapsed for the purpose of inserting it into or of removing it from a shoe.

An object of this invention is to provide 15 a last with a lock or detent which is positively held out of engagement with an abutment with which it cooperates to hold a last expanded. Another object of the invention is to provide a lock or detent which is movable 20 to engage a fixed part on the last part on which the lock or detent is mounted. A still further object of the invention is to provide a bonding means rigidly secured to the part on which a detent is movably mounted 25 and having a fixed portion with which the detent may engage when moved from locking position so as to be held positively away from locking position, provision being made on the other member of 30 the last which will effect automatically this connection between the detent or lock and the fixed part of the bonding means on the movement of the last to collapsed position. Another and further 35 object of the invention is to provide a detent or lock which has two movements, one a pivoted movement toward and from an abutment for locking the last in an expanded condition, and the other a sliding movement 40 with reference to its axis of turning to cause said detent or lock to be held out of engagement with the abutment. Still another and further object of the invention is to provide an interlocking means between a lock 45 and detent and a bonding member which will hold the detent out of cooperation with an abutment with which it engages to lock the last in expanded condition. Another and still further object of the invention is to 50 provide an improved construction by which the detent and bonding member are held together so that they may be simultaneously fitted to the last.

To these and other ends, the invention

consists of certain parts and combinations 55 of parts, all of which will be hereinafter described, the novel features being pointed out in the appended claims.

In the drawings: Fig. 1 is a vertical section through a last 60 showing the latter locked in expanded position;

Fig. 2 is a fragmentary sectional view showing the lock or detent depressed prior to the collapse of the last;

Fig. 3 is a fragmentary sectional view showing the manner in which the detent or lock cooperates with a stop or abutment for the purpose of freeing the detent from its locked depressed position;

Fig. 4 is a sectional view showing the last collapsed after the lock or detent has been freed to the action of its spring;

Fig. 5 is a view showing the manner in which the detent and bonding member are 75 held together prior to being inserted in the last;

Fig. 6 is an edge view of the parts shown in Fig. 5; and

Fig. 7 a detail view showing the adjustable pin or abutment.

In the illustrated embodiment of the invention there is provided two last parts namely; a heel part 1 and a toe part 2. The two parts are held together by a bonding 85 means which, in this instance, comprises a plate 4 secured in a kerf 5 in the heel part by transversely retained pins 6, the bonding means being extended beyond the heel part into a kerf 7 formed in the opposite faces 90 of the toe part 2. This projecting portion has a pivot pin 3 extending therethrough, the pivot pin bridging the kerf 7. The last parts may be cut above the pivot pin to provide a space 8 and cooperating 95 faces 9 and 10 are provided respectively on the heel and toe part concentric with the axis of turning between the parts to provide greater bearing surface between the last parts. Shoulders 11 may be formed on the 100 heel and the toe part to limit the swinging movement of the parts in one direction.

The locking of the last in expanded position may be effected through a lock or detent 12. This lock or detent has two movements 105 one into and out of cooperation with an abutment piece 13, which will hereinafter be more particularly described, and the other for the

purpose of effecting a locking of the detent out of cooperation with the abutment, so that the last may be maintained unlocked while in an expanded condition. In this instance, the detent has a pivoted as well as having a bodily or sliding movement, this result in this embodiment being secured by bridging the kerf 5 with a pivot pin 14 and providing the detent with a slot 15. A shoulder 16 is provided on the upper side of the detent and this shoulder is adapted to engage with the abutment piece 13 in the manner illustrated in Fig. 1, thereby preventing the collapsing of the last. In order to collapse a last the detent is depressed, and with the end in view of maintaining this depressed position a locking device is employed preferably in the form of a shoulder or abutment 17 formed, in this instance, on the bonding plate 4. With this shoulder a shoulder 18 on the detent engages, the sliding or bodily movement of the detent permitting such engagement. In order to effect such engagement the detent has a face 19 which cooperates with an inclined or cam face 20 on the bonding piece 4 leading to the shoulder 17, this cooperation taking place on the depression of the detent or lock. A helical spring 21 acts on the detent to move the latter toward locking position and also to maintain the detent locked in depressed position. This helical spring, in this instance, has an abutment with a projection 22 on the detent, and an abutment at 23 with the bonding plate or member 4, pressure of the spring being in the direction to move the detent bodily towards its axis of turning as well as to swing said detent about said axis. With the end in view of effecting automatically the release of the detent from its locking device when the last is collapsed, so that, on the expansion of the last, the detent will, under the action of the spring, move into cooperative relation with the abutment 13, there is provided a suitable means, such as a stop or abutment 24 in the form of a pin, bridging the kerf 7 in front of the pivot 3, and this pin or abutment 24 cooperates with the face 19 of the detent 12 on the latter part of the collapsing movement of the last, as illustrated in Fig. 3. A farther movement of the last shifts the detent 12 out of engagement with the locking shoulder 17 and permits the detent under the action of the spring 21 to move upwardly until the surface 25 of the detent cooperates with the abutment 13 in the manner illustrated in Fig. 4. It follows that upon the expansion of the last, the surface 25 will ride along the under side of the abutment 13 until the shoulder 16 is reached when said detent will again move upwardly to bring the shoulder 16 in abutment with the abutment 13, as illustrated in Fig. 1.

In this embodiment the bonding member 4 and the detent 12 are formed from metal

plate material, and these two parts lie in a singular plane within the kerfs 5 and 7, the detent being slightly thinner than the bonding member 4 so that it has freedom of movement in the kerfs. The bonding member 4 preferably has a recess 4^a in which the pivot end of the detent 12 projects, the portion 4^b above the recess acting as a filler for the kerf 5 above the detent. The under side of this portion 4^b or the top wall of the recess 4^a also enables the detent and the bonding member to be connected in the manner illustrated in Fig. 5, so that the detent and the bonding plate may be simultaneously inserted in the kerfs of the last. It is necessary in order to hold the parts together that the spring 21 exert a pressure on the detent to maintain the upper surface of the latter adjacent with the pivot in cooperation with the top wall of the recess 4^a while the detent engages with the abutment or shoulder 17. After the parts have been inserted in the kerfs the insertion of the pivot pin 14 through the detent 12 will destroy this cooperation and permit the swinging of the detent 12 free of any engagement with the bonding member adjacent to the pivot of the detent.

The abutment 13 is adjustable to compensate for wear between such abutment and the detent 12 and to this end this abutment is mounted in notches cut in the front face of the recess on opposite sides of the kerf. The abutment has its abutment face 13^a tapered from one end of the abutment piece to the other and by the longitudinal adjustment of the abutment piece a portion of this abutting face 13^a is brought into position for cooperation with the detent and in this way provision is made for compensation for wear between the detent and the abutment piece. Pins 18^b pass through the abutment piece 13 into the fore part 7 of the last and secure the abutment piece in its adjusted position.

The operation of the invention will be understood from the foregoing but it may be summarized as follows:

Assuming that the last parts are in the positions shown in Fig. 1 and it is desired to collapse the last; downward pressure is applied on the detent 12 until the detent interlocks with the bonding member 4. The last may be held in this unlocked position any desired length of time and upon being collapsed the detent will cooperate with the stop or abutment 24, shown in Fig. 3, causing the release of the detent from the bonding member so that when the last is expanded the detent will reengage with the abutment 13.

From the foregoing it will be seen that there has been provided a locking detent which is positively held out of locking position after being manually shifted out of locking position. This detent is furthermore automatically released upon the col-

lapse of the last so that it may be returned to a position where it will lock the last in expanded position. The detent has two movements, one toward and from the abutment preferably a pivot movement and the other into and out of position where it may be held positively against return to the locking position, the latter movement, in this instance, being effected through the sliding or shifting of the detent with reference to its turning axis. The means for locking the detent out of locking position is preferably effected by establishing interlocking relation between the detent and a bonding member, which is rigidly secured to a last part on which the detent is mounted. The spring acts on the detent to hold the latter in detaining position and also to hold the detent interlocked with the bonding plate or member, and when the detent is in detaining position the spring prevents the interlocking except on compression of the spring. The detent and the bonding member lie in one plane and the detent is slightly thinner than the bonding member so that binding thereof in the kerfs can not take place. The abutment with which the detent cooperates is adjustable to compensate for wear between the abutment and the detent. The last is inexpensive to manufacture, simple in operation and durable in use.

What I claim as my invention and desire to secure by Letters Patent is:

1. A last comprising two last parts, a bonding member rigidly secured to one of said last parts and pivotally connected with the other of said last parts, a detent mounted on the part to which the bonding member is rigidly secured, an abutment mounted on the other of said last parts, and cooperating portions on the bonding member and the detent for holding the detent out of interlocking relation with the abutment.

2. A last comprising two last parts, a detent mounted on one of said last parts, an abutment mounted on the other of said last parts for cooperating with the detent to lock the last in an expanded position, means movable with the last part on which the detent is mounted for cooperating with the detent to hold the latter out of locking relation with the abutment, and means mounted on the last part, that carries the abutment for cooperation with the detent in order to effect the release of the latter upon the collapsing of the last.

3. A last comprising two last parts, a bonding member rigidly secured to one of said last parts and pivotally connected to the other of said last parts, an abutment on said last mentioned last part, a detent mounted upon the last part to which the bonding member is rigidly secured, cooperating portions on the detent and the bonding member for holding the detent out of lock-

ing relation with the abutment, and a stop on the last part carrying the abutment for cooperating with the detent in order to effect the release of the detent from the bonding member when the last is collapsed. 70

4. A last comprising two last parts movably connected together, an abutment on one of said last parts, a detent on the other of said last parts having a pivoted and a sliding movement, and means for cooperating 75 with the detent for effecting sliding movement of the detent upon the depression of the latter and for holding said detent out of locking relation with the abutment and means cooperating with the detent for effecting a sliding movement of said detent to release the latter.

5. A last comprising two relatively movable last parts, an abutment mounted on one of said last parts, a detent mounted on the other of said last parts and adapted to cooperate with said abutment to prevent the collapsing of the last, a part fixed to the last part on which the detent is mounted, said part being adapted to cooperate with the 85 detent to hold the latter out of locking relation with the abutment, and means mounted on the last part on which the abutment is arranged for cooperating with the detent to effect the movement of the latter 90 out of cooperation with the first part. 95

6. A last comprising two last parts having opposed kerfs, a bonding member rigidly secured in the kerf of one of said parts and pivotally mounted in the kerf of the other of said parts, a detent pivotally mounted in the kerf of the part to which the bonding member is rigidly secured, an abutment secured to the other of said parts and cooperating portions on the bonding member 100 and the detent for holding the detent out of locking relation with the abutment. 105

7. A last comprising two last parts having opposed kerfs, a bonding member rigidly secured in the kerf of one of said parts 110 and pivotally mounted in the kerf of the other of said parts, a detent pivotally mounted in the kerf of the part to which the bonding member is rigidly secured, an abutment secured to the other of said parts, cooperating portions on the bonding member and the detent for holding the detent out of locking relation with the abutment, and means for cooperating with said detent to release the same from the bonding member 115 upon the collapsing of the last so that the detent may be in a position to cooperate with the abutment upon the expansion of the last. 120

8. In combination with a bonding member provided with a recess, a detent having a portion arranged in said recess and a portion interlocking with the bonding member, and a spring arranged between the bonding member and the detent for holding the de- 125 130

tent in engagement with one wall of the recess and the interlocking portions in engagement.

9. A last comprising two last parts each provided with a kerf, the opposed faces of last parts being cut to provide a space between such parts when the last is in expanded position, an abutment carried by one of the last parts, a pivotally mounted detent arranged on the other of said last parts within the kerf thereof and adapted to cooperate with the abutment to hold the last in an expanded condition, and a bonding member rigidly secured in the kerf of the last part on which the detent is arranged and pivotally mounted in the kerf of the other last part, said bonding member having a portion extending above the pivot of the detent and filling the kerf above said detent.

10. A last comprising two pivotally connected last parts, the opposed faces of the last parts above the pivot being cut away to provide a space and the last parts each being provided with a kerf, one of said last parts also being provided with notches in one wall of the space on opposite sides of the kerf in said wall, an abutment piece fitted in said notches, and a detent pivotally mounted in the kerf of the opposite wall of the space and adapted to cooperate with said abutment member.

11. A last comprising two pivotally connected last parts, a detent mounted on one of said last parts, and an abutment with which said detent cooperates to lock the last in an expanded position, said abutment being adjustable on the other of said last parts to compensate for wear between the abutment and the detent.

12. A last comprising two pivotally connected last parts, a detent pivoted to swing about an axis transversely of the longitudinal axis of the last and an abutment adjustable transversely of the longitudinal axis of the last to compensate for wear between the abutment and the detent.

13. A last comprising two pivotally connected last parts each provided with a kerf, a detent pivotally mounted in the kerf of one of said last parts, and an abutment for engagement by said detent to lock the last in an expanded condition, said abutment bridging the kerf of the other last part and being adjustable transversely of the kerf to bring different portions thereof in position for engagement by the detent to compensate for wear.

14. A last comprising two movably connected last parts, an abutment on one of said last parts, a pivoted and slidably mounted detent on the other last part for cooperation with the abutment, to lock the last in an ex-

panded position, a device for cooperating with the detent to lock the latter out of locking relation with the abutment, and a spring acting on the detent to hold the latter in cooperative relation with the abutment or in cooperative relation with the device for locking the detent out of locking relation with the abutment.

15. In a last, a heel part and forepart, a bonding member arranged to permit relative movement of the last parts to collapse the last, a locking member and an abutment against which it presses for holding the last in extended position, said locking member being arranged to hook over the bonding member when moved from last locking position, and an abutment arranged to move relatively to the locking member in the last length changing movement and to press against and unhook the locking member.

16. In a last, a heel part and forepart, a bonding member arranged to permit relative movement of the last parts to collapse the last, a locking member for holding the last in extended position and arranged to hook over the bonding member when moved from last locking position, and an abutment below the locking member arranged to move relatively to the locking member in the last length changing movement and to press against and unhook the locking member.

17. In a last, a heel part and a forepart, a bonding plate fast in one part and pivoted in the other to enable the collapsing of the last, a locking member with one end mounted in that last part in which the plate is fast, and abutting the other part to hold the last in extended position, and arranged to interlock its other end with the pivoted end of the plate to hold it out of last-locking position when removed therefrom, and a pin located near the pivot of the plate arranged to open the interlock as the length of the last changes.

18. A last comprising two last parts, a hinge member pivotally connecting said last parts, a detent pivoted and slidably mounted on one last part, an abutment on the other last part arranged to be engaged by the detent to lock the last positively in extended position, the detent being arranged to move downwardly out of cooperation with the abutment and then longitudinally of the last, a cam on the hinge member to give the detent the said longitudinal movement when depressed, a hook on the detent arranged to slip over the cam and hold the detent out of locking position, and a spring arranged to oppose both the said downward movement and the said longitudinal movement of the detent.

JOHN C. SCHELTER.
